UNITED STATES PATENT OFFICE

2,329,485

SUPPLEMENTAL METALLIC WINDOW UNIT

Henry N. Renton, Wyndote, Pa., assignor to The American Pulley Company, Philadelphia, Pa., a corporation of Pennsylvania

Original application June 1, 1940, Serial No. 338,416. Divided and this application June 24, 1942, Serial No. 448,211

14 Claims. (Cl. 160—105)

This invention relates to supplemental metallic window units, that is to say to additional units for incorporation in regular window structures of a permanent type, and characterized by having sliding glazed storm sashes for winter use, and sliding screen sashes for summer use, the present application being a division of a U. S. Patent #2,295,685, granted to me on September 15, 1942.

Amongst the objects of my invention are to enable the component parts of a supplemental window unit of the kind referred to to be assembled in a permanent window structure without requiring the aid of any special tools, and without the need of screws, bolts or other fastening devices to subsequently hold them in place; and to make possible the ready and quick interchange of the glazed and screen sashes without necessitating the removal of other parts of such unit.

Still another object of my invention is to attain the foregoing advantages in a supplemental window unit which is simple in construction, and whereof the sash frame parts and the sash guides lend themselves to expeditious manufacture from sheet metal at relatively small cost.

Other objects and attendant advantages will appear from the following detailed description of the attached drawings, wherein

Fig. 1 shows the outside elevation of a metallic window structure with a supplemental or auxiliary unit conveniently embodying my invention.

Fig. 2 is a vertical sectional view of the organization taken as indicated by the angled arrows II—II in Fig. 1.

Fig. 3 is a horizontal section taken as indicated by the angled arrows III—III in Figs. 1 and 2.

Fig. 4 is a broken-out perspective view of one of the sash guide elements of my improved supplemental window unit.

Fig. 5 is a view corresponding to Fig. 2 with screen sashes substituted for the glazed sashes shown in the latter illustration.

Fig. 6 is a fragmentary sectional view taken as indicated by the angled arrows VI—VI in Fig. 5.

Figs. 7 and 8 are fragmentary cross sectional views taken as indicated respectively by the angled arrows VII—VII and VIII—VIII in Fig. 6.

With reference first more particularly to Figs. 1—4 of these illustrations, the permanent sheet metal window structure there shown for convenience of exemplifying my invention is identi-

cal with that featured in the co-pending application hereinbefore referred to, the sides or jambs of its frame being indicated at 1, the head or lintel at 2, and the sill at 3, these being all of hollow formation. As seen in Fig. 3, the jambs 1 have their inner faces medially recessed longitudinally as at 4 and are provided at the outside and inside corners with box beads 5 and 6. Secured centrally of the jambs 1 by means of screws 7 are parting strips 8 of U shaped cross sectional configuration whereof the longitudinal flanges serve as guides for upper and lower sliding sashes 9 and 10, the lintel 2 of the window frame being longitudinally recessed as at 11 to receive the top edge of the upper sash, and the sloping surface 12 of the sill being stepped as at 13 for engagement by the bottom rail of the lower sash 10, all as shown in Fig. 2.

The supplemental window unit, with which the present invention is more especially concerned, includes a pair of auxiliary jamb or sash guide strips 15 whereof one is shown in perspective in Fig. 4. Although these strips may be otherwise formed, they are here shown as fashioned from sheet metal to the approximate cross sectional configuration of the letter W, and are so proportioned that their central ridges 16 frictionally fit over the outer box beads 5 on the jambs 1 of the main or permanent window, which beads extend inwardly of the window opening as shown in Fig. 3. The sides of the central ridges 16 of each auxiliary jamb strip 15 are depressed inwardly from opposite sides to form stop shoulders 17 which bear against the corner beads 5 of the corresponding main jambs 1 and thus determine the position of said strips in the main window structure. The outer walls 18a and 19a of the reversely positioned outer ridges 18 and 19 of each jamb strip 15 provide, in conjunction with the central ridge 16, parallel sash guiding grooves 20 and 21. From Figs. 2 and 4 it is to be noted that the grooved side wall 18a of the strip 15 extends downwardly to near the middle of the main window structure, and that the grooved side wall 19a extends upwardly to the same extent. The purpose served by this construction will be explained later on herein.

My improved supplemental window unit further includes upper and lower glazed sliding sashes 24 and 25 to correspond with those of the main window. As shown in Figs. 2 and 3, the frame of the upper sash comprises a top bar 26 and side bars 27 of Z cross section, and a bottom bar 28 of W cross section whereof the outer trough is disposed in the plane of the other three bars, said

bars being all permanently united at corners preferably by welding. Set into the frame of the upper sash 24 is a glass pane 29 whereof the edges are enveloped by compressible weathering 30 which may be of felt or rubber. The laterally projecting flanges of the side bars of the upper sash frame are sheathed by conformative strips 31 fashioned from relatively thin non-corroding metal. As shown in Fig. 3, the sheathed projecting side flanges of the upper sash frame 24 are snugly engaged within the corresponding grooves or guideways 20 of the auxiliary jamb strips 15 and the sheathing strips are extended inwardly of the window frame at the outer face of the upper sash to act as retainers for the glass pane 29. The top bar 26 of the upper sash is likewise provided with a sheathing strip 32 which is like the strips on the side bars except for being fashioned to provide a groove for the retainment of a compressible hollow sealing strip 33 of rubber or the like to bear against the under-side of the lintel 2 of the main window frame, as shown in Fig. 2. The projecting flanges of the top and side bars are apertured at intervals of their length as instanced at 35 in Fig. 2 and the metal of the sheathing strips is depressed inwardly from opposite sides of said flanges into these apertures. In this simple way it will be seen that the sheathing strips are effectively secured without the aid of additional fastening means. To the bottom bar 28 of the upper sash 24 is suitably secured a strip 36 of thin non-corroding spring sheet metal of which a free edge portion 36a extends downward into the inner trough of said bar.

The frame of the lower sash 25 likewise has top and side bars 37 and 38 of Z cross section which are reversed in position with respect to the corresponding bars of the upper sash. The bottom bar 39 of the lower sash 25 is also of Z cross section, but reversed in position with respect to the other bars 37 and 38 of said sash, said several bars being permanently united at corners preferably by welding like those of the upper sash. The side bars of the lower sash are similarly provided with sheathing strips 40 of non-corroding metal which are similarly secured to the outstanding flanges of said bars, said flanges extending respectively into the guide grooves 21 of the auxiliary jamb strips 15 as shown in Fig. 3. The sheathing strip 41 on the top cross bar 37 of the lower sash 25 is extended outwardly as shown in Fig. 2 and then downwardly as at 42 to cooperate with the free spring portion 36a of the strip 36 on the bottom rail 28 of the upper sash 24, thereby to form a weather-seal at that region when the sashes are in closed position. The sheathing strip 43 on the bottom cross bar 39 of the lower sash 25 is fashioned to provide a longitudinal recess for the retainment of a compressible hollow packing strip 45 of rubber or the like which is adapted to bear weather-tight against the top surface of the sill 12 of the main window structure. As shown, the sheathing strips 40 and 41 on the top and side bars 37 and 38 are extended inwardly at the inside face of the sash 25 and the strip 43 on the bottom bar 39 extends inwardly at the outside face of said sash to retain the glass pane 46. While the outer walls 18a and 19a of the grooves 20 and 21 in the auxiliary jamb strips 15 exert frictional pressure on the side flanges of the two sashes 24 and 25, such pressure is not sufficient to hold the sashes in shifted position. I have accordingly provided the sashes respectively with suitable catches 47 and

48 whereof the slide bolts are adapted to respectively engage suitably allocated openings 49 and 50 in the auxiliary jamb strips 15. Due to the interruption of the guide grooves 20 and 21 in 5 the auxiliary jamb strips 15 approximately midway of the height of the window, as hereinbefore pointed out, it is possible to remove the upper sash 24 from below and the lower sash 25 from 10 of the grooves being bent outwardly somewhat as at 18b and 19b in Fig. 4 to facilitate such removal. In this connection, it is to be noted from Fig. 3 that the width of the two sashes 24 and 25 is such that the auxiliary jamb strips 15 are 15 held in place by them, as a consequence of which, the component parts of the supplemental window unit can be readily and quickly installed or removed from the main window structure.

The provision made for the ready removal of 20 the glazed sashes 24 and 25 also makes possible the ready substitution of upper and lower sliding screen sashes such as shown at 54 and 55 in Figs. 5-8. The frame of the upper screen sash 54, see Figs. 5 and 7, has top, bottom and side bars 25 56, 57 and 58 all formed to hollow channel cross sectional configuration with their hollows facing outward and with their outstanding flanges in a common plane, the flanges of the side bars 58 extending into the guide grooves 20 in the auxiliary jamb strips 15. Stretched across the opening of the upper screen sash frame is a sheet of wire mesh 59 which is held in place by a clamp frame 60 whereof the bars are of U shaped cross sectional configuration, the latter frame being 30 inserted, flange edges foremost, into the hollows of the main frame with the margins of the screening 59 engaged as clearly shown in Figs. 5 and 7. The outstanding flanges of the several bars of the main frame of the sash 54 are 35 sheathed by strips 61, 62 and 63 of non-corroding metal which are extended inwardly to overlap the corresponding bars of the clamp frame 60 thereby to hold the latter in place. The main frame of the lower screen sash 55 differs from the 40 corresponding frame of the upper screen sash 54 in that its top, bottom and side bars 64, 65 and 66 are of L cross sectional configuration with outstanding flanges in a common plane whereof those at the side bars 66 fit into the guide grooves 45 21 of the auxiliary jamb strips 15 as shown in Fig. 8. The wire mesh 67 for the lower sash 55 is clamped by a clamp frame 68 in a manner similar to that described of the upper screen sash 54 while sheathing strips 69, 70 and 71 of 55 non-corroding metal serve to hold the clamp frame in place. Catches 72 and 73 are provided to hold the upper and lower screen sashes 54 and 55 in open or closed positions, the slide bolts of 60 these catches being adapted to engage the same apertures 49 and 50 in the auxiliary jamb strips 15 which serve the catches 47 and 48 on the glazed sashes 24 and 25. In addition to the catches the lower screen sash 55 is fitted with handles as instanced at 74 in Fig. 6 for convenience of raising and lowering it.

Having thus described my invention, I claim:

1. A supplemental window unit for use in connection with permanent windows of buildings, including a pair of auxiliary jamb strips each 70 integrally fashioned from sheet metal with a hollow central ridge to fit snugly over an inwardly-extending bead projection on the corresponding jamb of the permanent window, and with parallel sash guiding grooves respectively at opposite sides of said central ridge; and upper

and lower sliding sashes with side edge portions engaged in the corresponding sash guiding grooves of the two auxiliary jamb strips.

2. A supplemental window unit according to claim 1, in which the auxiliary jamb strips are formed with stop shoulders; and in which the width of the sashes is such as to hold the auxiliary jamb strips in place with their shoulders abutting the inner faces of the bead projections of the permanent window.

3. A supplemental window unit according to claim 1, in which the side edge portions of the sashes engaged in the guide grooves of the auxiliary jamb strips are sheathed with conformative facing strips of non-corrosive metal.

4. A supplemental window unit according to claim 1, in which the sashes are formed from metal with side flanges to engage the guide grooves in the auxiliary jamb strips; in which the flanges of the sashes are sheathed with conformative facing strips of non-corrosive metal; and in which the sheathing strips are held in place by indentation into apertures arranged at spaced intervals in the side flanges of the sash frames.

5. A supplemental window unit according to claim 1, in which the outer walls of the grooves of the respective auxiliary jamb strips extend downward and upward respectively from the top and bottom ends of said strips and terminate approximately midway of the height of the window, so that one sash can be inserted or removed from above, and the other sash inserted or removed from below.

6. A supplemental window unit according to claim 1, further including retractable catches on the sashes which are engageable with apertures in the central ridge of the auxiliary jamb strips to secure the sashes in closed position.

7. A supplemental window unit for use in connection with permanent windows of buildings, including a pair of auxiliary jamb strips each integrally fashioned from sheet metal with a hollow central ridge to fit snugly over an inwardly-extending bead projection on the corresponding jamb of the permanent window, and with parallel sash guiding grooves respectively at opposite sides of said central ridge; and upper and lower sliding sashes with frames having metallic side bars of Z cross-section with their outwardly-extending flanges engaged in corresponding sash guiding grooves of the two auxiliary jamb strips, and with transparent panes whereof the side edges are set into the inner angle hollows of said side bars.

8. A supplemental window unit according to claim 7, in which the outwardly-extending flanges of the sash frame side bars are sheathed with conformative facing strips of non-corrosive sheet metal.

9. A supplemental window unit according to claim 1, in which the upper sash has a metallic frame including Z section top and side bars with the outwardly-extending flanges of said side bars projecting into corresponding guide grooves in the supplemental jamb strips, and a W section bottom bar whereof the outer trough is in the plane of the other rails, a transparent pane fitted into a recess jointly provided by the inner angles of the several frame bars, conformative sheathing strips of non-corrosive sheet metal engaged over the outer flanges of the side bars and marginally lapping the pane, a similar sheathing strip engaged over the upwardly-projecting flange of the top bar and providing, with said flange,

a retaining channel for a resilient weathering insert to engage the frame lintel of the permanent window, and a spring strip secured to the inner flange of the aforesaid bottom bar and having a free edge portion within the inner trough of the W; and in which the lower sash has a metallic frame with Z section top and side bars which are reversely arranged in respect to the corresponding bars of the top sash, with the projecting flanges of said side bars extending into the other pair of grooves in the auxiliary jamb strips, a bottom Z bar reversely positioned with respect to the others, a transparent pane fitted into the recess jointly provided by the several frame bars, sheathing strips of non-corrosive metal engaged over the outer flanges of the side bars and perimetrical lapping the pane as in the top sash, and sheathing strips engaged over the projecting flanges and the top and bottom bars, the sheathing strip on the top bar of the lower sash being extended outward and downward into weather sealing engagement with the free portion of the spring strip on the bottom bar of the upper sash, and the sheathing strip on the bottom bar of the lower sash being flanged to provide with the outstanding flanges of said bottom bar, a retaining channel for resilient weathering to engage the sill of the permanent window.

10. A supplemental window unit for use in connection with permanent windows of buildings, including a pair of auxiliary jamb strips each integrally fashioned from sheet metal with a hollow central ridge to fit snugly over an inwardly-extending bead projection on the corresponding jamb of the permanent window, and with parallel sash guiding grooves respectively at opposite sides of said central ridge; and upper and lower sliding sashes with side edge portions engaged in the corresponding sash guiding grooves of the two auxiliary jamb strips in which the sashes are glazed; and further including screen sashes which are interchangeable with the glazed sashes.

11. A supplemental window unit for use in connection with permanent windows of buildings, including a pair of auxiliary jamb strips each integrally fashioned from sheet metal with a hollow central ridge to fit snugly over an inwardly-extending bead projection on the corresponding jamb of the permanent window, and with parallel sash guiding grooves respectively at opposite sides of said central ridge; and sliding screen sashes having metallic frames with hollow top, bottom and side bars providing outstanding perimetrical flanges around the frames, the side portions of said flanges engaging the other corresponding grooves in the auxiliary jamb strips, wire mesh panels, clamp frames with top, bottom and side bars to fit into the hollows of the corresponding frame bars of the respective sashes and to clamp the margins of the wire mesh within said hollows, and conformative sheathing strips fitting over the projecting flange portions of the respective sash frames and marginally lapping the clamp frames to hold them in place on the sashes.

12. A supplemental window unit according to claim 11, in which the bars of the clamp frames are of U cross-sectional configuration and engage flanges-first into the sash frame hollows.

13. A supplemental window unit according to claim 1, wherein the frame of the upper sash comprises channeled metallic top, bottom and side bars with outstanding flanges whereof those

at the sides engage corresponding grooves in the auxiliary jamb strips, a wire mesh panel, a clamp frame whereof the bars fit into the channels of the corresponding sash frame bars to clamp edge margins of the panel within said channels, and conformative sheathing strips fitting over the projecting flanges of the sash frames and marginally lapping the clamp frames to hold the latter in place on the sash; and wherein the frame of the lower sash comprises a metallic frame with top, bottom and side bars of L cross-section providing a perimetric flange whereof the side portions engage in the other corresponding grooves of the auxiliary jamb strips, a wire mesh panel, a clamp frame with top bottom and side bars fitting into the angle hollows of the corresponding lower sash frame bars to clamp the edge margins of the panel, and conformative sheathing strips fitting over the projecting flange portions of the lower sash frame bars and marginally lapping the clamp frame to hold the latter in place.

14. A supplemental window unit according to claim 1, in which the upper sash has a metallic frame including Z section top and side bars with the outwardly-extending flanges of said side bars projecting into corresponding guide grooves in the supplemental jamb strips, and a W section bottom bar whereof the outer trough is in the plane of the other rails, a transparent pane fitted into a recess jointly provided by the inner angles of the several frame bars, conformative sheathing strips of non-corrosive sheet metal engaged over the outer flanges of the side bars and marginally lapping the pane, a similar sheathing strip engaged over the upwardly-projecting

flange of the top bar and providing, with said flange, a retaining channel for a resilient weathering insert to engage the frame lintel of the permanent window, and a spring strip secured 10 to the inner flange of the aforesaid bottom bar and having a free edge portion within the inner trough of the W, said sheathing strips being all secured by indentation into spaced apertures in the corresponding frame bars of the sash; and 15 in which the lower sash has a metallic frame with Z section top and side bars which are reversely arranged in respect to the corresponding bars of the top sash, with the projecting flanges of said side bars extending into the other pair of grooves in the auxiliary jamb strips, a bottom Z bar reversely positioned with respect to the others, a transparent pane fitted into the recess jointly provided by the several frame bars, 20 sheathing strips of non-corrosive metal engaged over the outer flanges of the side bars and perimetrical lapping the pane as in the top sash, and sheathing strips engaged over the projecting flanges and the top and bottom bars, the sheathing strip on the top bar of the lower sash being 25 extended outward and downward into weather sealing engagement with the free portion of the spring strip on the bottom bar of the upper sash, and the sheathing strip on the bottom bar of the lower sash being flanged to provide with the outstanding flanges of said bottom bar, a retaining channel for resilient weathering to engage the sill of the permanent window, the sheathing strips of said lower sash being secured in the same manner as those of the upper sash.

HENRY N. RENTON.
